UNITED STATES PATENT OFFICE

CHARLES F. RUBSAM, OF JACKSON, MICHIGAN

RIM TOOL

Application filed April 2, 1923. Serial No. 629,373.

The invention relates to devices or tools for opening and closing transversely split demountable tire-rims.

The object of the invention is to provide an improved device for this purpose which can be easily and quickly applied and removed from the rim, is efficient in operation, and simple in construction.

The invention consists in the several novel features hereinafter set forth and more particularly defined by the claims at the conclusion hereof.

In the drawing: Fig. 1 is a side elevation of a tool embodying the invention, applied to a closed rim. Fig. 2 is an inverted plan. Fig. 3 is a side elevation showing the tool operatively applied to hold the rim open. Fig. 4 is a perspective of the tool disassociated from the rim. Fig. 5 is a detail perspective of the hook for locking the tool to one end of the rim. Fig. 6 is a detail perspective of the combined driving and locking plate which is fixed on one end of the rim. Fig. 7 is a transverse section taken on line 7-7 of Fig. 1. Fig. 8 is a perspective of a modified form of rim-plate.

The invention is exemplified in a device or tool for operating a demountable tire-rim which comprises a base A and integral side flanges α' and is obliquely split at α^2 to permit the rim to be opened and contracted, and expanded and closed, as well understood in the art. A plate 10 is secured by rivets 11 to the inner periphery of the rim adjacent one of its ends and extends across the split and under the contiguous end of the rim. This plate is provided with an opening 13 to receive a radially extending stud or lug 14 which is riveted to said contiguous end 40 of the rim, to lock the rim-ends against longitudinal separation. This plate is provided with notches 15 which are adapted to fit around and receive a bolt on the body of the wheel to form a driving-connection between the wheel-body and the rim. The corners 10 α of the plate 10 are undercut or curved to adapt the plate to radially interlock with the operating tool as will presently appear.

The improved tool comprises a member 16 which is adapted to be hooked to the plate

10, so as to be locked radially thereto; a cross-pin 17, pivotally connected to member 16 and adapted to extend through notches 15 to lock member 16 longitudinally to the plate 10; an arm 18 rigid with pin 17 so it will fulcrum in member 16; a transverse pin 19, riveted to the distal end of the arm; and a bearing-block or member 20 pivotally held on pin 19 and adapted to bear against and ride on the inner periphery of the end of the rim which carries the lug 14 to initially effect relative radial movement of the rim-ends to disengage said lug from plate 10, and thereafter engage one face of the lug 14, to effect relative longitudinal movement of the rim-ends to contract the rim, when the arm is turned about its fulcrum in member 16. Member 16 comprises sides 16 α adapted to straddle the plate-sides or flanges 12 and having portions 16 β adapted to hook into or interlock with the undercut portions 10 α of the plate and an integral connecting base 16 ϵ . Pivot-holes 16 δ are formed in sides 16 α in which the fulcrum-pin 17 is removably held by a stud 17 α which is fixed to said pin. Member 16 is formed with a transverse notch 16 ϵ through which stud 17 α will pass to permit the endwise removal of the fulcrum-pin from said member and its insertion therein. The purpose of a removable connection between the fulcrum-pin and member 16 is to permit the member 16 to be separately slipped into hooked relation with plate 10 from one end of the latter and then shifted longitudinally while it is radially locked, to bring pivot-hole 16 δ into alignment with notches 15, so the fulcrum-pin can be inserted endwise through holes 16 δ and said notches to longitudinally lock member 16 and the fulcrum-pin with respect to the rim-end which carries plate 10. As soon as the arm 18 is rotated relatively to member 16, stud 17 α will pass out of registry with notch 16 ϵ so that the fulcrum will be automatically locked against endwise withdrawal from member 16 and plate 10 at all times, except when the rim is closed. Bearing-block 20 is notched, as at 21, to receive and transversely interlock with rim-lug 14. The block 20 is reversible, so either of its ends will be operative to en-

gage stud 14. Arm 18 is provided with a hexagonal end 23, so a wrench may be applied to turn the arm.

In operation, member 16, while separated from pin 17, will be placed against the inner face of the rim adjacent one of the ends of plate 10 and then slipped longitudinally of the plate into hooked relation therewith and until pivot-holes 16^a register with notches 15 in plate 10. Fulcrum-pin 17 will then be inserted endwise through holes 16^a and notches 15, so that member 16 will then be locked radially to plate 10 and longitudinally by the fulcrum-pin, whereupon the pin will be operative to serve as a fulcrum for the arm 18. By applying a wrench to end 23 of arm 18, the latter will swing relatively to plate 10, so that pin 19 will operate block 20 against the inner periphery of the rim-end which carries lug 14 and initially effect relative radial shift of the rim-ends to disengage stud 14 from opening 13 and unlock the rim-ends for relative longitudinal movement or so the rim may be contracted. Thereafter, block 20 will ride on the rim until it encounters lug 14 and then the continued swing of the arm will force said lug and one rim-end into the other until the rim is contracted to the extent desired, as shown in Fig. 3. In such position, the inherent spring of the rim will be applied through lug 14 and the fulcrum-pin, so that the tool will be automatically retained to hold the rim contracted, as shown in Fig. 3. To close the rim, it is only necessary to swing the arm back to the position shown in Fig. 1. During such swing, the resiliency of the rim will cause lug 14 to follow the block 20 until it reaches opening 13 in the rim and thereafter the block will move away from said lug and swing radially inward, to permit the lug to pass into said opening and lock the rim. When the rim is closed, the stud 17^a will be in registry with notch 16^e in member 16, so the fulcrum can be withdrawn from said member. Upon withdrawal of the fulcrum-pin, the member 16 can be slipped longitudinally off the plate 10.

A somewhat different form of rim-plate with which the improved tool is adapted to be used is illustrated in Fig. 8, in which a plate 10^c is riveted to one end of the rim, is extended to lap under the other end of the rim and provided with a lug 20^a which is adapted to pass into a slot in the latter end of the rim. This plate is formed of cast metal and has a radially inward projecting lug 21^a formed with a recess 22^a to receive one of the cross bolts on the wheel body to form a driving connection for the rim. The side edges of plate 10^c are curved, as at 23^a, to receive the hook portions 16^b of tool member 16. In using the tool on this type of rim, member 16 may be slipped into hooked engagement and shifted until holes 16^a are

aligned with the recess 22^a, whereupon the cross-pin 17 may be inserted through said holes and recess to lock member 16 to the plate. The operation of the tool upon this rim will be similar to the operation already described.

The invention exemplifies a tool which can be readily locked to a rim without any devices on the rim in addition to the usual locking and driving connection between the rim-ends; in which a member is adapted to be hooked to the driving-plate; in which the hook-member is separable from the fulcrum-pin; in which the fulcrum-pin is adapted to pass through the usual notches in the rim-plate; and in which the second member is adapted to engage the rim-end locking-lug.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. A tool for operating split rims comprising an arm, a member in which the arm is removably fulcrumed having integral means to hook onto the edges of a plate on the inner periphery of one end of a rim and lock it radially thereto, and a member on the arm to engage the other rim-end. 95
2. A tool for operating split rims comprising an arm, a member in which the arm is fulcrumed, provided with sides adapted to slide onto and interlock radially with a plate on the inner periphery of one rim-end, and a connecting portion to extend under the plate, and a member to engage the other rim-end. 100
3. A tool for operating split rims comprising an arm, a member having a transverse opening therein and provided with means to interlock radially with a plate on one rim-end, a fulcrum-pin on said arm and slidably endwise into and out of said opening, and a member on the arm for engaging the other rim-end. 105
4. A tool for operating split rims comprising an arm, a member having a transverse opening therein and provided with means to interlock radially with a plate on one rim-end, a fulcrum-pin on said arm and slidably endwise into and out of said opening, means between the pin and said member to automatically lock them together when the arm is turned, and a member on the arm for engaging the other rim-end. 115
5. A tool for operating split rims comprising an arm, a member having a transverse opening therein and provided with means to interlock radially with a plate on one rim-end, a fulcrum-pin on said arm and slidably endwise into and out of said opening, a stud and recess connection between the pin and said member to lock the pin against with- 125

drawal, and a member on the arm for engaging the other rim-end.

6. A tool for operating a demountable split rim having its ends provided respectively with elements projecting inwardly from its inner periphery to interlock them circumferentially, comprising a member provided with means formed to hook into radially interlocked relation with one of the elements, the member and means being adapted when in their hooked position to extend completely within the inner periphery of the rim; and an operating arm to which said member is pivotally connected, provided with means to bear against and slide on the inner periphery of the other rim end when the arm is operated while the member is in its hooked position with said element to separate the rim ends radially and until arrested by the other element.

20 7. A tool for operating a split demountable rim having its ends provided respectively with an interlocking plate and lug, comprising a member having means to radially interlock with the plate, and an operating arm to which said member is pivoted, provided with means to engage the end of the rim carrying the lug, said arm being movable to radially separate the rim ends and unlock the plate and lug and to slide the means into engagement with the lug after the rim-ends have been separated.

Signed at Jackson, Michigan, this 17th day of March, 1923.
